RAILWAY TRAFFIC CONTROLLING APPARATUS

Application filed November 24, 1931. Serial No. 577,065.

My invention relates to railway traffic controlling apparatus, and more specifically to apparatus for the elimination of an undesirable signal indication under certain traffic conditions. In particular, my invention is directed toward the elimination of a momentary green flash produced by a light signal when a light weight, high speed rail vehicle passes from one track section into the next.

I will describe one form of railway traffic controlling apparatus embodying my invention, and will then point out the novel features thereof in claims.

In the accompanying drawing, I have shown a stretch of railway track divided by insulated joints into sections A—B and B—C, each having the usual source of energy 2, and a track relay designated by the reference character T with a distinguishing exponent. Traffic entering the section A—B is controlled by a light signal S^A, and traffic leaving the section B—C is controlled by a similar light signal S^C. Signals S^A and S^C are three-aspect color light signals of the type wherein one lamp in conjunction with one reflector and lens combination is capable of providing three distinct indications by means of three movable, translucent, colored roundels placed in the path of the light beam and actuated by a three-position polarized relay mechanism.

Each signal S^A and S^C comprises a rotatable armature 3 to which are affixed the colored roundels G, R and Y. Armature 3 is polarized in any suitable manner as, for example, by the field from a permanent magnet or electromagnet, so that its direction of rotation will depend upon the polarity of current supplied to winding 4. The structure of signals S^A and S^C is not shown in detail as it forms no part of my present invention.

When winding 4 of signal S^A is deenergized, armature 3 which is biased by gravity to its neutral position will cause roundel R to occupy a position in front of the lamp L,

displaying a red signal, and contacts 8—28 and 9—30 actuated by armature 3 will be closed. When winding 4 is energized with current of a given polarity which I shall term the normal polarity, armature 3 will rotate in the clockwise direction to the position indicated in the drawing, whereby a green signal will be displayed and contacts 8—27 and 9—30 will be closed. If the polarity of current supplied to winding 4 is reversed, armature 3 will rotate in the counter-clockwise direction, placing roundel Y in front of the lamp L to display a yellow signal, and contacts 8—28 and 9—29 will become closed.

It has been found that in circuits of the type commonly used in connection with this type of signal, a fast moving, light weight locomotive or gasoline-electric car passing from one track section to the next, as for example, out of track section B—C, might cause track relay T² to become energized before track relay T³ has sufficient time to release, under which condition, for a short interval of time, both relays T² and T³ would be picked up. Therefore, signal S^A which had been displaying a red indication due to opening of the circuit for winding 4 of this signal at contacts 23 and 24 of relay T², would display a momentary false green flash prior to the instant when the train shunt became effective to release relay T³. That is, the simultaneous energization of relays T¹, T² and T³, for a short interval of time is sufficient to cause an undesirable green flash to be given by signal S^A prior to the steady yellow indication produced following the release of relay T³. A similar result might follow should a light car enter the track section B—C at high speed, in which case relay T¹ might pick up before relay T² became released.

In the circuit embodying my invention, I interpose a front contact of the slow pick-up relay R^A in the circuit for lamp L of signal S^A in such manner that when current of nor-

mal polarity is applied to winding 4, a green indication will not be given until relay R^A first picks up and closes the lamp circuit at front contact 14. The pick-up time interval of relay R^A is chosen of sufficient length to insure that lamp L will not become illuminated until after relay T^3 releases, following a pick-up of relay T^2 , under the most adverse traffic conditions. The objection to the momentary dark signal which results when lamp

10 L is extinguished during the interval of the green flash is small as compared with the objection to the false green flash itself.

15 To explain in greater detail the manner in which the apparatus functions, I shall describe the operations involved first, when a car passes slowly from left to right through the section A—C, and then, when the same car passes points B and C at high speed.

20 When the car occupies track section A—B, winding 4 of signal S^A is deenergized at contacts 5 and 6 of track relay T^1 , and armature 3 is caused by gravity to assume its neutral position in which roundel R becomes placed in front of lamp L. Signal S^A will display a red indication because lamp L will be illuminated by virtue of a circuit starting at one terminal X of a suitable source, contact 8—28 of the mechanism of signal S^A , wire 13, wire 22, and lamp L to the other terminal O of the same source. When the car enters section B—C at slow speed, signal S^A will continue to display red, because, although contacts 5 and 6 of relay T^1 will have become closed, contacts 23 and 24 of relay T^2 will be opened prior to the closing of contacts 5 and 6 of relay T^1 , so that winding 4 of relay T^1 will continue to remain deenergized.

25 When the car passes at slow speed beyond point C, relay T^2 will pick up after relay T^3 will have become released. The release of relay T^3 will deenergize winding 4 of signal S^C and relay R^C will become deenergized due to opening of contact 8—27 of the mechanism of signal S^C . The release of relay R^C will cause current of reverse polarity to be applied to winding 4 of signal S^A over a circuit starting at one terminal X of a suitable source, wire 31, back contact 16 of relay R^C , wire 19, front contact 24 of relay T^2 , wire 26, front contact 6 of relay T^1 , winding 4 of signal S^A , front contact 5 of relay T^1 , wire 25, front contact 23 of relay T^2 , wire 20, back contact 15 of relay R^C , and wire 18 to the other terminal O of the source. Armature 3 of signal S^A will now rotate in the counter-clockwise direction from its neutral position, causing signal S^A to display a yellow indication.

30 Assume now that the car passes point B at high speed and relay T^1 picks up before relay T^2 releases, so that winding 4 of signal S^A will receive an impulse of current of normal polarity over front contact 7 of relay T^3 , front contacts 15 and 16 of relay R^C , and front contacts 23 and 24, and 5 and 6, of relays T^2

and T^1 , respectively. When this occurs, contact 8—28 of signal S^A will open, extinguishing lamp L, and contact 8—27 will close, applying energy to the slow pick-up relay R^A . By the time relay R^A picks up to close the lamp circuit at front contact 14 of relay R^A , relay T^2 will have become released and signal S^A will have returned to its deenergized or red position with no green flash intervening.

35 Similarly, when the car passes point C at high speed and relay T^2 picks up before relay T^3 releases, winding 4 of signal S^A will receive an impulse of current of normal polarity, as before, and the pick-up interval of relay R^A will again be effective in preventing illumination of lamp L for an interval of time sufficient to permit relay T^3 to release.

40 One advantage of apparatus embodying my invention is that I have provided means for eliminating a false green signal flash which might occur under certain traffic conditions by substituting a momentary dark signal therefor, without interfering in any manner with the normal sequence or speed of response of signal indications as commonly obtained under usual traffic conditions.

45 Although I have herein shown and described only one form of railway traffic controlling apparatus embodying my invention, it is understood that various changes and modifications may be made therein within the scope of the appended claims without departing from the spirit and scope of my invention.

50 Having thus described my invention, what I claim is:

1. Railway signaling apparatus comprising in combination, an electric lamp, a first circuit for energizing said lamp, a mechanism including a winding for causing said lamp to display one indication when said winding is energized and another indication when said winding is deenergized, means governed by traffic conditions for at times energizing said winding, a slow pick-up relay, a first contact controlled by said mechanism for energizing said slow pick-up relay when said winding is energized, a second contact controlled by said mechanism for energizing said first circuit when said winding is deenergized, and a second circuit for energizing said lamp governed by said slow pick-up relay.

55 2. Railway signaling apparatus comprising in combination, an electric lamp, a first and a second circuit for energizing said lamp, a mechanism including a winding for causing said lamp to display one indication when said winding is energized and another indication when said winding is deenergized, means governed by traffic conditions for at times energizing said winding, a slow pick-up relay, means effective when said winding is energized for energizing said slow pick-up relay, means effective when said winding

is deenergized for energizing said first circuit, and means governed by said slow pick-up relay for energizing said second circuit.

3. Railway signaling apparatus comprising in combination, an electric lamp, a first and a second circuit for energizing said lamp, a mechanism including a winding for causing said lamp to display one indication when said winding is energized and another indication when said winding is deenergized, means governed by traffic conditions for at times energizing said winding, a slow pick-up relay, means effective when said winding is energized for energizing said slow pick-up relay, means effective when said winding is deenergized for energizing said first circuit, and a contact controlled by said slow pick-up relay for energizing said second circuit.

4. Railway signaling apparatus comprising in combination, an electric lamp, a first and a second circuit for energizing said lamp, a mechanism including a winding for causing said lamp to display a first, second, or third indication according as said winding is deenergized, energized with current of normal polarity, or energized with current of reverse polarity, respectively; means governed by traffic conditions for at times energizing said winding with current of normal polarity for at other times energizing said winding with current of reverse polarity, and for at still other times deenergizing said winding; a slow pick-up relay, means effective when said winding is energized with current of either normal or reverse polarity for energizing said slow pick-up relay, means effective when said winding is either deenergized or is energized with current of reverse polarity for energizing said first circuit, and means governed by said slow pick-up relay for energizing said second circuit.

5. Railway signaling apparatus comprising in combination, an electric lamp, a circuit for energizing said lamp, a mechanism including a winding for causing said lamp to display one indication when said winding is energized and another indication when said winding is deenergized, means governed by traffic conditions for at times energizing said winding, a slow acting contact included in said lamp circuit and governed by said winding in such manner that said contact becomes closed a definite time interval after said winding is energized, and means governed by said winding effective when said winding is deenergized for short circuiting said slow acting contact.

6. In combination, a stretch of railway track divided into the usual block sections, a source of energy and a track relay for each block section; a light signal for governing traffic into one of said block sections comprising an electric lamp, an energizing circuit therefor, a winding, and a mechanism governed by said winding for causing said lamp

to display one indication when said winding is energized and another indication when said winding is deenergized; means governed by the track relay associated with said one block section for at times energizing said winding, means effective when said winding is energized for preventing the energization of said lamp circuit until after the expiration of a predetermined time interval, and means effective when said winding is deenergized for energizing said lamp circuit.

7. In combination, a stretch of railway track divided into the usual block sections, a source of energy and a track relay for each block section; a light signal for governing traffic into one or more of said block sections comprising an electric lamp, a first and a second energizing circuit therefor, a winding, and a mechanism governed by said winding for causing said lamp to display one indication when said winding is energized and another indication when said winding is deenergized; an energizing circuit for said winding including a front contact of each of two track relays associated with two adjoining block sections immediately in advance of said signal, a time measuring device, means governed by said winding for energizing said time measuring device when said winding is energized, means governed by said winding for energizing said first lamp circuit when said winding is deenergized, and means governed by said time measuring device effective after the expiration of a definite time interval following the energization of said device for energizing said second lamp circuit.

8. In combination, a stretch of railway track divided into the usual block sections, a source of energy and a track relay for each block section; a light signal for governing traffic into one or more of said block sections comprising an electric lamp, and a mechanism including a winding for causing said lamp to display a first, second or third indication according as said winding is deenergized, energized with current of normal polarity, or energized with current of reverse polarity respectively; means for energizing said winding with current of normal polarity when and only when three track relays associated with three adjoining block sections immediately in advance of said signal are energized, means for energizing said winding with current of reverse polarity when and only when two track relays associated with two adjoining block sections immediately in advance of said signal are energized and a third track relay associated with the third block section in advance of said signal is deenergized, means for deenergizing said winding when either or both of two track relays associated with two adjoining block sections immediately in advance of said signal are deenergized, a slow pick-up

- relay; a first, second and third contact controlled by said winding closed respectively when said winding is energized with current of normal polarity, when said winding is energized with current of reverse polarity, and when said winding is deenergized; a circuit for energizing said slow pick-up relay having two branch paths one of which includes said first contact and the other of which includes said second contact, and a circuit for energizing said lamp having two branch paths one of which includes said third contact and the other of which includes a front contact of said slow pick-up relay.
- 15 In testimony whereof I affix my signature.
